SPRING COVER

Filed Oct. 26, 1927

INVENTOR.
GEORGE W. TOFT
BY *George W. Toft*
ATTORNEYS.

UNITED STATES PATENT OFFICE

GEORGE W. TOFT, OF MOUNTAIN VIEW, CALIFORNIA

SPRING COVER

Application filed October 26, 1927. Serial No. 228,950.

My invention relates to improvements in spring covers, and it consists in the combinations, constructions, and arrangements hereinafter described and claimed.

- 5 An object of my invention is to provide a spring cover for collapsible tubes, in which the cover is instantly returned to cover the mouth of the tube as soon as the handle of the cover is released.
- 10 A further object of my invention is to provide a device of the type described in which the entire device is supported by a cap that may be threaded upon the end of the tube to take the place of the usual cap.

- 15 Other objects and advantages will appear in the following specification, and the novel features of my invention will be particularly pointed out in the appended claim.

My invention is illustrated in the accompanying drawing forming a part of this application, in which:

Figure 1 is a section along the line 1—1 of Figure 5;

Figure 2 is a section along the line 2—2 of 25 Figure 1;

Figure 3 is a perspective view of the spring;

Figure 4 is a development of the cover and the handle; and

30 Figure 5 is a top plan view of the device.

In carrying out my invention I make use of a collapsible tube 1 having a mouth portion 2 and a threaded stem 3. A cap 4 is threaded upon the tubular member 3, and

35 has a pair of lugs 5 which straddle a handle 6.

The development of the handle is shown in Figure 4. The handle has ends 7 with openings 8 therein for receiving a pintle 9. This pintle is passed through the lugs 5 and

40 supports a spring 10, shown in Figure 3.

Figure 4 shows the handle 6 as carrying a cover portion 11. The periphery of this cover may be bent downwardly along the dotted line 12 shown in Figure 4 to grip a

45 resilient stopper 13, which is shown to be hemispherically in shape in Figure 1. The cap 4 has a seat 14 for receiving the resilient member 13.

The spring 10 has one end 15 secured to 50 the handle 6 by a clip 16, while its other end

is turned at right-angles as at 17, and bears against one of the lugs 5, see Figures 2 and 5.

From the foregoing description of the various parts of the device, the operation thereof may be readily understood.

55 The spring 10 urges the cover into closed position. The cover is opened against the tension of the spring when the handle 6 is depressed. As soon as the handle is released the cover will instantly swing into closed position, thus sealing the contents of the tube 1.

60 The cap 4 may be screwed upon the tubular member 3 and takes the place of the usual cap, provided with the tube. With the device it is unnecessary for the operator to remove 65 the standard cap and replace it each time he wishes to remove a portion of the contents from the tube. A mere pressure on the handle 6 opens the mouth 2 and permits the contents to be squeezed therethrough. When 70 the tube is set down, the cover 11 instantly swings into closed position and hermetically seals the device.

75 The device is extremely simple in construction, and provides a self-supporting unit that may be screwed onto a standard collapsible tube.

80 Although I have shown and described one embodiment of my invention, it is to be understood that the same is susceptible of various changes and I reserve the right to employ such changes as may come within the scope of the appended claim.

I claim:

85 A spring cover comprising a cap having a bore therethrough which terminates at the top in a rounded cavity, said cap having a threaded portion adapted to be screwed onto a receptacle, a lever pivotally carried by said cap and having a resilient rounded stopper receivable in said rounded cavity, and 90 spring means for seating said stopper when said lever is released.

GEORGE W. TOFT.
